UNITED STATES PATENT OFFICE.

VILHELM MAYER, OF CHICAGO, ILLINOIS, ASSIGNOR, BY MESNE ASSIGNMENTS, TO
U. S. SAMPLE COMPANY, A CORPORATION OF ILLINOIS.

BEVEL-CUTTING MACHINE.

Application filed September 10, 1919. Serial No. 322,785.

To all whom it may concern:

Be it known that I, VILHELM MAYER, a citizen of the United States, and a resident of Chicago, in the county of Cook, State 5 of Illinois, have invented certain new and useful Improvements in Bevel-Cutting Machines, of which the following is a specification.

My invention relates to bevel cutting machines and particularly to an improved attachment for straight paper cutting machines which will enable bevel cutting to be readily and efficiently accomplished by such machines.

15 The invention is particularly useful in the binding art for beveling thick heavy sheets of paper, composition, or similar material which are used for covers of books. The usual type of straight cutting machine is 20 one comprising a supporting table, work adjusting mechanism, and a knife blade adapted to be reciprocated at right angles with and toward and away from the table. The object of my invention is to provide a simple 25 adjustable attachment for machines of this type for supporting the paper board at the proper angle with reference to the knife so that when the knife descends the desired bevel cut will be accomplished.

30 My invention is particularly applicable to and useful in connection with the paper cutting machine disclosed in my co-pending application executed of even date herewith Serial Number 322,784, filed September 10, 35 1919. On the accompanying drawings I have shown my improved attachment applied to such machine and on these drawings

40 Fig. 1 is a front elevational view of the machine with the attachment applied thereto,

Fig. 2 is a side elevational view,

Fig. 3 an enlarged sectional view on plane 3—3, Fig. 1, and

45 Figs. 4 and 5 are perspective views of blocks employed in the construction.

The supporting structure of the paper cutting machine shown comprises the two side frames 5 and 6, the upper cross beam 7, the lower cross-beam 8, and the work supporting bed or table 9. Above the table the side frames have vertical guide channels 10 and 11 of which the bars 12 and 13 50 form the front walls. The cutting knife structure comprising the body 14 and the 55 blade 15 reciprocates in these channels. The extension 16 on the side frame 5 has the diagonally extending slot 17 in which rollers 18 pinned on the knife structure engage. This roller and slot connection 60 causes the knife structure to move diagonally in the well known manner.

At the ends of the knife structure body are the balls 19 and 20 which are received by the bearing heads 21 and 22. These 65 bearing heads are connected by adjustable links 23 and 24 with similar bearing heads 25 and 26 which receive the ball ends of crank pins 27 and 28 extending from the hub 29 and fly-wheel 30 respectively, the 70 hub and fly-wheel being secured on the drive shaft 31 which is journaled in the bearings 32 and 33 on the side frames 5 and 6 respectively. The shaft also has a sprocket wheel 34 by means of which the machine 75 may be connected to the belt 35 with a suitable driving pulley.

At the rear edge of the work supporting table 9 is formed the rectangular recess 36 which receives the cutting stick when the 80 machine is used for ordinary straight cutting. This cutting stick is usually of wood and held in place in the recess by a clamping plate 37 held against the machine frame and the stick by screws 38. However when my 85 approved bevel cutting attachment is applied the wood cutting stick may be removed and the recess used for positioning and securing the attachment.

The attachment is supported by two blocks 90 39 and 40 which are of the same construction. These blocks support the blocks 42 and 47, which are adjustable with relation to the supporting blocks 39 and 40. These blocks 39 and 40 each have a rectangular 95 flange 41 extending downwardly from its inner end for engagement in the cutting stick recess 36. The pairs of blocks are arranged at the opposite sides of the work supporting table and against the side frames, 100 and are then secured by the clamping plate 37 pressing against the flanges 41 of the blocks 39 and 40. Mounted on the blocks 42 and 47 are the supporting frames A and B for the paper board guiding and holding frame C. The frame A comprises the block 12 which has the longitudinally extending slots 43 whereby it may be adjustably secured on the block 39 by screws 44. Extending upwardly from the block 42 at the 110

rear and outer sides thereof is the wall 45 which has the opening 46.

The frame B is similar to the frame A and comprises the block 47 which is adjustably mounted on the block 40 by means of screws 48 engaging in longitudinally extending slots (not shown) similar to those in the block 42 of frame A. The block 47 has also the vertical wall 49 provided with the hole 50.

The guiding and holding frame C comprises a wall 51 from the upper end of which the shelf 52 extends forwardly at right angles. Extending laterally from the wall 51 are the pins 52 and 53 which have bearing in the holes 46 and 50 in the ears 45 and 49 respectively. The ear 45 being higher than the ear 49, the walls 51 and 52 will be inclined to or at an angle with reference to the machine bed, but with the lower edge of the wall 52 in a plane parallel with that of the cutting edge of the knife 15.

Extending upwardly at the left and right ends respectively of the wall 51 are the arms 54 and 55. The arm 54 has hinged thereto the link 56 which link has the longitudinally extending slot 57 for receiving the bolt 58 which also passes thru the link 59 hinged at its lower end on the base 42 by means of the screw 60. The links 56 and 59 form an adjustable brace for setting the angle of inclination of the inner face of the wall 51 with reference to the cutting plane. In other words the angle of bevel can be varied by means of the adjustable brace. During lengthening or shortening of the brace the frame C trunnions on its pins 52 and 49.

Secured against the under side of the wall 51 is the stop plate 61 which projects a short distance throughout its length beyond the front lower corner of the wall 51 in order to offer a supporting ledge 61' for the work to be beveled. The edge of the ledge is parallel with and against the vertical cutting plane of the knife blade and when the work is held against the face of the wall 51 and the ledge the descending knife will bevel the supported edge of the work. To automatically hold the work in position

against the wall and ledge a pressure plate 62 is provided, this plate having pins 63 and 64 extending forwardly at its ends and thru the arms 54 and 55, compression springs 65 encircling the pins between the arms and the abutment nut 66. Before insertion of work the plate 62 is held along its lower part against the wall 51 by the springs 65. When work such as a sheet of paper board is to be beveled along one edge, the board is slid on such edge along the shelf 52 until it encounters the pressure plate 62, and then with a little pressure the board is slid downwardly between the pressure plate and the wall 51 and against the ledge 61' in which position it is held while the knife descends

and makes the bevel cut. In order to take up any spring in the board and to offer a solid backing therefor during the cutting operation, the lower part of the abutment face of the wall 51 deflects gradually outwardly so that the wall presents a gradually curved surface which snugly receives the end of the board projecting below the pressure plate. Then when the knife descends this projecting end cannot give but is rigidly backed up by the wall 51.

As the knife structure reciprocates its cutting edge is always horizontal, and the frame C is therefore inclined transversely of the machine, that is, its one side is higher than the other, in order that the knife will take a gliding or shaving cut, and not merely a pressure cut. The transverse movement of the knife during reciprocation thereof will assist in this shaving cut and a smooth and clean cut results, and there will be no ragged or fringed edges. Neither will the fibres of the paper board be pulled apart as would be the case under direct pressure cutting.

I thus produce a very desirable and efficient beveling attachment for paper cutting machines which can be quickly and accurately applied. By means of the adjustable brace, and the adjustable supporting bases the attachment can be quickly set for the desired angle of bevel. The operator need then only insert work into place to successively bevel the edges thereof as desired. I do not of course desire to be limited to the exact construction, arrangement and operation shown and described as modifications can no doubt be made which would still come within the scope of my invention.

Having described my invention, I claim as follows:

1. In an attachment for paper cutting machines, the combination of means for supporting the paper to be beveled, a member which is adapted to be removably secured to the cutting machine, and a member secured for adjustment with respect to the first mentioned member and supporting the paper supporting member.

2. In an attachment for paper cutting machines, the combination of means for supporting the paper to be beveled, a member which is adapted to be removably secured to the cutting machine, and a member secured for adjustment with respect to the first mentioned member, said means for supporting the paper being mounted upon and arranged at an angle to the adjustable member.

3. In a paper cutting machine, the combination of a supporting table, a knife, means for reciprocating said knife in a plane at right angles with said table, and an attachment for supporting card board to be cut on the bevel by said knife, said attachment

comprising a wall in front of the cutting plane, a ledge at the lower end of said wall, means for clamping a sheet to be beveled against the face of said wall and on said ledge, and means for tilting said wall to an angle with said cutting plane whereby upon descent of said knife the lower edge of said board will be cut on the bevel.

4. In a paper cutting machine, the combination of the supporting table, a knife above said table, means for reciprocating said knife in a plane at right angles with said table, and a beveling attachment, said attachment comprising a supporting wall in front of the cutting plane inclined from said plane, a plate secured to the lower end of said wall and projecting a distance therefrom to form a seating ledge for card board to be cut, the front edge of said ledge being parallel with and against the cutting plane, and means for clamping a card board sheet against said wall and on said ledge whereby upon descent of said knife the presented edge of said sheet will be cut away on the bevel, and means for varying the angle of inclination of said wall.

5. A bevel cutting attachment for paper cutting machines comprising two supporting frames, a supporting board trunnioned at its ends on said frames to be tilted, means for locking said board in tilted position, a ledge at the lower front corner of said board forming a seat for the work to be beveled, and clamping mechanism for clamping the work against said board above said ledge.

6. In a paper cutting machine, the combination with a paper cutting machine having a supporting table, a knife, and means for reciprocating said knife in a plane at right angles with said table, said table having a cutting stick channel below the knife, of a beveling attachment comprising blocks supported on said table at the sides thereof and having flanges extending therefrom into said cutting stick channel, supporting frames on said blocks adjustable longitudinally thereon, an abutment wall extending between said frames and trunnioned thereon, said wall being higher at one side than at the opposite side whereby it is inclined in a direction transversely of said table, an adjustable brace connected between one of said frames and said wall for adjusting the tilting of said wall and securing it in tilted position with reference to the cutting plane, means for clamping against said wall a board to be beveled, said wall being positioned to present the lower edge of the clamped board thru the cutting plane whereby said edge will be cut on the bevel when the knife descends.

7. A bevel cutting attachment for paper cutting machines comprising two supporting frames, a supporting board trunnioned

at its ends on said frame to be tilted, means for locking said board in tilted position, a ledge at the lower front corner of said board forming a seat for the work to be beveled, and clamping mechanism for clamping the work against said board above said ledge, said board having its front face deflecting gradually outwardly towards said ledge so that the work will be compressed during the beveling operation, such compression together with the ledge support keeping the beveled edge solid and intact.

8. In an attachment for paper cutting machines, the combination of means for supporting the paper to be beveled, a member which is adapted to be removably secured to the cutting machine, and a member secured for adjustment with respect to the first mentioned member, said paper support being pivoted for adjustment with relation to the adjustable member.

9. In an attachment for paper cutting machines, the combination of means for supporting the paper to be beveled, a member which is adapted to be removably secured to the cutting machine, a member secured for adjustment with respect to the first mentioned member, said paper support being pivoted for adjustment with relation to the adjustable member, and means for locking said paper support in adjusted position.

10. In an attachment for paper cutting machines, the combination of means for supporting the paper to be beveled, a member which is adapted to be removably secured to the cutting machine, a member secured for adjustment with respect to the first mentioned member, said paper support being pivoted for adjustment with relation to the adjustable member, and means for locking said paper support in adjusted position, said means being arranged between the paper support and the adjustable member.

11. In an attachment for paper cutting machines, the combination of means for supporting the paper to be beveled, a member which is adapted to be removably secured to a cutting machine, and a member secured for adjustment with respect to the first mentioned member, said first members being adapted to be secured and removed from the cutting machine as a unit.

12. In apparatus of the class described, a guillotine cutting machine, an attachment therefor comprising a support adapted removably to fit upon the machine table, an intermediate means adjustable on the support, an inclined paper supporting member adjustably pivoted on the intermediate means, and means for clamping the paper to the paper supporting member.

13. In apparatus of the class described, a guillotine cutting machine, an attachment therefor comprising a support adapted re-

movably to fit upon the machine table, an intermediate means adjustable on the support, an inclined paper supporting member adjustably pivoted on the intermediate means, and means for clamping the paper to the paper supporting member, said intermediate means being adjustable whereby the

lower edge of the paper supporting member may be adjusted relatively to the cutting plane of the knife.

10

In witness whereof, I hereunto subscribe my name this 5th day of September, A. D. 1919.

VILHELM MAYER.
